United States Patent

Des. 240,005
Patented May 25, 1976

240,005

BENDER OR STRAIGHTENER

Donald R. Humphreys, Topsfield, Mass., assignor to
Custom Radius Corporation, Topsfield, Mass.

Filed Oct. 15, 1974, Ser. No. 514,410

Term of patent 7 years

Int. Cl. D8—05

U.S. Cl. D8—32

Fig. 2

FIG. 1 is a perspective view of a bender or straightener; and

FIG. 2 is a view in end elevation of the device shown in FIG. 1, as seen when looking from left to right in that view.

I claim:

The ornamental design for a bender or straightener, substantially as shown and described.
